(57) **CLAIM**

The ornamental design for a cartridge for optical genome mapping, as shown and described.

DESCRIPTION

FIG. 1 is a top-front-right isometric view of a cartridge for optical genome mapping embodying our new design;

FIG. 2 is an enlarged view of area 2 in FIG. 1;
FIG. 3 is a bottom-back-left isometric view thereof;
FIG. 4 is a front elevation view thereof;
FIG. 5 is a back elevation view thereof;
FIG. 6 is a left elevation view thereof;
FIG. 7 is a right elevation view thereof;
FIG. 8 is a top plan view thereof;
FIG. 9 is a bottom plan view thereof;
FIG. 10 is an exploded top-front-right isometric view thereof showing five exploded parts (a first part, a second part, a third part, a fourth part, and a fifth part, from top to bottom);

FIG. 11 is an enlarged view of area 11 in FIG. 10;
FIG. 12 is an enlarged view of area 12 in FIG. 10;
FIG. 13 is an exploded bottom-back-left isometric view thereof showing the five exploded parts (the first part, the second part, the third part, the fourth part, and the fifth part, from bottom to top);

FIG. 14 is an enlarged view of area 14 in FIG. 13;
FIG. 15 is a top-front-right isometric view of the second part thereof;
FIG. 16 is a bottom-back-left isometric view of the second part thereof;

FIG. 17 is a front elevation view of the second part thereof;
FIG. 18 is a back elevation view of the second part thereof;
FIG. 19 is a left elevation view of the second part thereof;
FIG. 20 is a right elevation of the second part view thereof;
FIG. 21 is a top plan view of the second part thereof;
FIG. 22 is a bottom plan view of the second part thereof;
FIG. 23 is a top-front-right isometric view of the third part thereof;
FIG. 24 is a bottom-back-left isometric view of the third part thereof;

FIG. 25 is a front elevation view of the third part thereof;
FIG. 26 is a back elevation view of the third part thereof;
FIG. 27 is a left elevation view of the third part thereof;
FIG. 28 is a right elevation view of the third part thereof;
FIG. 29 is a top plan view of the third part thereof;
FIG. 30 is a bottom plan view of the third part thereof;
FIG. 31 is a top-front-right isometric view of the fourth part thereof;

FIG. 32 is a bottom-back-left isometric view of the fourth part thereof;
FIG. 33 is a front elevation view of the fourth part thereof;
(Continued)

FIG. 34 is a back elevation view of the fourth part thereof; FIG. 35 is a left elevation view of the fourth part thereof; FIG. 36 is a right elevation view of the fourth part thereof; FIG. 37 is a top plan view of the fourth part thereof; and, FIG. 38 is a bottom plan view of the fourth part thereof. The shade lines show contour and not surface ornamentation.

Broken lines are used to illustrate portions of a cartridge for optical genome mapping that form no part of the claimed design.
